UNITED STATES PATENT OFFICE.

ARTHUR S. THOMAS, OF MINNEAPOLIS, MINNESOTA.

STORM-WINDOW SUPPORT.

1,317,242.

Specification of Letters Patent. Patented Sept. 30, 1919.

Application filed December 9, 1915. Serial No. 65,883.

To all whom it may concern:

Be it known that I, ARTHUR S. THOMAS, a citizen of the United States, residing at Minneapolis, in the county of Hennepin and State of Minnesota, have invented certain new and useful Improvements in Storm-Window Supports, of which the following is a specification.

My invention relates to storm-window supports and has for its object to provide means for holding a storm-window which is hingedly connected at its top in any desired angular position for opening the same to a greater or less degree, said holding means operating automatically to hold the same in any of the said positions.

The full objects and advantages of my invention will appear in connection with the detailed description thereof and are particularly pointed out in the claim.

In the drawings, illustrating the application of my invention in one form—

Figure 1 is a sectional elevation of a storm-window having my invention applied thereto when in closed position. Fig. 2 is a view similar to Fig. 1 with the window held partly open. Figs. 3 and 4 are fragmentary views of the holding means showing how the same is secured to the sash and jamb, respectively. Figs. 5, 6 and 7 are detail views showing the manner of constructing the frictional joint. Figs. 8 and 9 are plan and sectional side views of a different form of joint connection of link 20 with plate 16.

As shown, the storm-window 10 is hingedly suspended, as indicated at 11, in a well-known way. The holding device comprises a plate 12 which is secured directly to the side of the sash 10 by screws 13, as best shown in Figs. 3 and 4. The plate 12 carries a lug or bracket 14 extending at right angles thereto to which is pivotally secured an arm or link 15. A second plate 16 is secured to the side of the jamb by means of screws 17, as clearly shown in Fig. 4, said plate 16 having a toe piece 18 extending at right angles to the plane of plate 16, which toe piece is engaged by a spring catch 19 secured to plate 12 whereby the window is held locked when the same is closed. A link or arm 20 is pivotally connected to plate 16, preferably by means of a large screw 21

which extends through said plate and into the body of the jamb. The links 20 and 15 are pivotally united at 22 by means of a friction joint, which will hold said links in any desired relative position. As shown in Figs. 1, 2 and 5, this joint may comprise a series of registering indentations 23 in the engaging body of the arms 15 and 20 held in engagement by means of a rivet 24. As shown in Figs. 6 and 7, an additional spring washer 25 may be employed, if desired, whereby a yielding pressure may be exerted upon the registering indentations 22.

As shown in Figs. 8 and 9, the plate 16 is provided with a key 26 which is pivotally connected to the plate 16. The key 26 has a tongue 27, and the arm 20 has an aperture 28 corresponding in size and shape to the key 26 and tongue 27. When said key is turned in one direction, as indicated in Fig. 8, the arm 20 may be applied thereto; and when the key is turned into the dotted-line position it will be effectively held where placed.

The operation of my device will be apparent when the storm-window is fully closed, as shown in Fig. 1. The arms 15 and 20 will hang parallel with the sash along the inside of the jamb and the catch 19 will lock over the toe piece 18 to hold the storm-window closed and locked. When it is desired to open the window the catches 19 will be lifted, and it is only necessary to push out the bottom of the window to the extent desired. The links 15 and 20 will be moved at the joint 22 and the friction of such joint will hold said links wherever set, which, in turn, operate to hold the window at any desired angle. It is simply necessary to push the window out or pull it in to open the same to the extent desired. It has been found in practice that wind has no effect upon the storm-window when so held by my holding device, the window remaining in the position held.

I claim:

In combination with a window frame and a storm window hingedly supported from the top of the window frame, a plate secured to the storm window, a spring catch connected with the upper end of said plate, a lug projecting from said plate toward the window frame, a link pivoted to said lug,

a plate secured to the window frame, a link pivoted to said last mentioned plate, said links being pivoted to each other at their ends remote from their pivotal attachment 5 to the window frame and storm window, and a toe piece projecting from the top of said last mentioned plate, said toe piece being adapted for engagement by said spring

catch when the storm window is fully closed.

In testimony whereof I affix my signature in presence of two witnesses.

ARTHUR S. THOMAS.
